UNITED STATES PATENT OFFICE

149,839

DESIGN FOR A BOAT

Walter B. Quigley, Columbus, Ohio

Application April 12, 1947, Serial No. 138,332

Term of patent 3½ years

(Cl. D71—1)

To all whom it may concern:

Be it known that I, Walter B. Quigley, a citizen of the United States, residing at Columbus, in the county of Franklin and State of Ohio, have invented a new, original, and ornamental Design for a Boat, of which the following is a specification, reference being had to the accompanying drawing, forming a part thereof.

Fig. 1 is a top plan view of a boat showing my new design;

Fig. 2 is a side elevational view thereof;

Fig. 3 is a front elevational view.

I claim:

The ornamental design for a boat, substantially as shown.

WALTER B. QUIGLEY.
